UNITED STATES PATENT OFFICE.

JOHN P. HOLLAND, OF NEWARK, NEW JERSEY.

SUBMARINE BOAT OR VESSEL.

SPECIFICATION forming part of Letters Patent No. 694,154, dated February 25, 1902.

Application filed July 31, 1901. Serial No. 70,414. (No model.)

To all whom it may concern:

Be it known that I, JOHN P. HOLLAND, a citizen of the United States, residing at Newark, in the county of Essex and State of New Jersey, have invented certain Improvements in Submarine Boats or Vessels, of which the following is a specification.

This invention relates to the class of boats or vessels that employ water ballast, which may be increased or diminished at will to permit the boat to dive or to come to the surface. Such boats are commonly denominated "submarine torpedo-boats," and are designed to be employed in time of war to launch torpedoes at the vessels of an enemy. One of the most important difficulties encountered in handling boats of this class, which are usually operated in bays, harbors, and estuaries along the coast, into which fresh water flows in considerable quantity, arises from the variable specific weight of the water at different points, due to different degrees of salinity, which of course produces material variation in the buoyant power of the water. In New York harbor, for example, the specific weight of the water varies at different points and at the same time over three hundred pounds in a volume of seventy-five tons, and this variation is found to be due to currents which change with the stages of the tides and with the direction and force of the wind. The inconvenience arising from this variation in the specific weight of the water is manifested in variations in the buoyancy of a submarine boat, and with the changing conditions of tide and wind these variations in specific weight will be manifested at the same point in a bay or harbor at different times. Therefore if the boat be adjusted for diving with the proper percentage of reserve buoyancy when the water in its vicinity shall have reached the maximum salinity and the ballast-tanks of the boat are filled without alteration or adjustment for buoyancy at the minimum salinity of the water of flotation the boat will sink to the bottom, or, under the reverse conditions, where the reserve buoyancy is adjusted for fresh water or for water of flotation having the minimum salinity the boat will not dive in water of the maximum salinity or specific weight.

If the boat's volume displaces seventy-five

tons in fresh water, 2.1744 tons of its volume will emerge or be exposed above the surface when the boat is placed in salt water of ordinary salinity. As the volume of reserve buoyancy is only about seven per cent. of this difference, it will be apparent that differences in the specific weight of the water in which the vessel operates must be provided for by means for changing the boat's total weight correspondingly, and it is of great importance to be able to effect this change quickly and in bad weather and also without the requirement of great care on the part of the person operating the boat. The present invention provides for this in the manner to be described hereinafter with reference to the accompanying drawings, wherein—

Figure 1 is a plan of the boat, broken away to show the water-ballast tanks in the bottom of the boat. Fig. 2 is a transverse section of the boat in the plane of the center of buoyancy of the boat indicated by line *v* in Fig. 3. Fig. 3 is a side elevation of the boat, broken away to show the ballast-tanks.

The hull or body *a* of the boat may be of the usual cigar shape. (Shown in Figs. 1 and 3.)

b is the propeller, *c* the rudders for diving, and *d* the conning tower or turret.

x designates in Fig. 3 the water line or level when the boat is light for surface running, with its ballast-tanks empty. The part *a'* of the boat's body above this line is called the "emerged" part and the part *a''* below the "submerged" part.

y designates the water line or level when the boat is awash and ready for diving, the ballast-tanks being filled.

The space in the boat containing the water ballast is usually divided up into receptacles called "tanks;" but as this dividing is merely constructive it will be convenient in order to make the present invention clear to consider the space within the boat for containing the necessary volume of water ballast to sink the boat in fresh water to the level of the line *y* as the "main" ballast-tank. This tank *T* has capacity to contain water enough to submerge the boat to the line *y* in fresh water—that is, to submerge the boat less the reserve buoyancy.

Because sea-water has more buoyancy than fresh water there will be more buoyancy to

overcome when the boat is operating in salt water than in fresh. Consequently an auxiliary tank t is provided with capacity sufficient to contain just water enough to serve 5 when the main tank T is full to submerge the boat in sea-water to the line y or put it awash for diving.

The features are shown somewhat diagrammatically in the drawings.

- 10 In placing the tank T in the boat its center of gravity must be forward of the boat's center of buoyancy such a distance that when this distance is multiplied by the volume of the ballast-tank the product will equal that 15 of the portion of the emersed body a' forward of the boat's center of buoyancy. The center of gravity cg of the tank T will be directly under the center of buoyancy e of the emersed portion a' of the boat in the transverse vertical plane indicated by the line w in Fig. 3. The auxiliary ballast-tank or group of tanks t will have its center of gravity in the same transverse plane (indicated by the line v in Fig. 3) as the center of buoyancy of the boat 20 when submerged to the line y .

As the tanks T and t are to be completely filled, no especial care will be required to effect the ballasting or the change of ballast—that is to say, if the boat be operating in fresh 25 water to prepare it for diving it will only be necessary to fill the tank T from the water of flotation. If it be operating in salt water, it will only be necessary to fill both of the tanks T and t , or if the boat be prepared for diving 30 in fresh water, the tank T being full, and it moves into salt water the tank t must also be filled. On the contrary, if it be operating in salt water and be awash, with both tanks T and t full, and then moves into fresh water 35 40 the water must be blown out of the tank t . This may be done by well-known means.

When the boat is prepared to dive in fresh or nearly fresh water and passes successively into water of greater salinity and finally into sea-water, the two tanks T and t will be filled 45 with water the weight of which per cubic foot is less than that of sea-water, and to compensate this another small tank t' is provided, this compensating tank being placed with its 50 center of gravity in the same transverse plane with that of the tank t . The tank t' will be of such capacity as to contain water enough to compensate by weight the difference between salt and fresh water sufficient to fill 55 the main tanks; but the volume of water therein will be variable. When operating in a mixture of salt and fresh water, a hydrometer will or may be employed to determine the specific weight of the water of flotation. 60 A reference to the scale of the hydrometer will indicate what quantity of water must be admitted to the tank t' in order to compensate properly the difference of salinity between the water in the tanks and the water 65 of flotation, so that the boat may dive prop-

erly and still have remaining the proper proportion of reserve buoyancy. For example, suppose the difference of displacement in volume between the boat's displacement in fresh and salt water is equivalent to seventy-six 70 cubic feet. The scale on the hydrometer will indicate zero in fresh water and will indicate the total volume of the tank t' in cubic feet—say seventy-six—when submerged in normal salt water. Now if the hydrometer indicates 75 "70" it shows that only seventy cubic feet of water ballast need be admitted to the tank t' to adjust the ballast for diving. The tank t' may have an ordinary float and indicator to indicate visually the amount. 80

I have not deemed it necessary to illustrate the means for filling the tanks and the hydrometer and float-indicator, as these are well-known devices and may be supplied by any one skilled in the art. This invention 85 relates to the relative capacities of the tanks for diving in water of different densities.

Having thus described my invention, I claim—

1. A submarine boat having a tank with 90 capacity, when full, for water ballast sufficient to put the boat in diving condition in fresh water, and an auxiliary tank with capacity, when both it and the main tank are full, to put the boat in diving condition in 95 salt water, said tanks being situated with reference to the center of buoyancy of the boat substantially as set forth.

2. A submarine boat having a tank with capacity, when full, for water ballast sufficient to put the boat in diving condition in 100 fresh water, said tank having its center of gravity situated directly below the center of buoyancy of the emersed portion of the boat, and an auxiliary tank with capacity, when 105 both it and the main tank are full, to put the boat in diving condition in salt water, said auxiliary tank having its center of gravity in the same transverse plane with the center of buoyancy of the boat, substantially as set 110 forth.

3. A submarine boat having a tank with capacity, when full, for water ballast sufficient to put the boat in diving condition in fresh water, an auxiliary tank with capacity, 115 when it and the main tank are full, to put the boat in diving condition in normal salt water, and a smaller compensating tank to provide ballast to compensate the difference between the weight of salt and fresh water 120 in the tanks, said tanks being situated with respect to the center of buoyancy of the boat, substantially as set forth.

In witness whereof I have hereunto signed my name, this 24th day of July, 1901, in the presence of two subscribing witnesses.

JOHN P. HOLLAND.
